INFANT'S SPOON

Robert M. Sweeney, Salisbury, Mo.

Application April 14, 1953, Serial No. 24,484

Term of patent 14 years

(Cl. D44—29)

To all whom it may concern:

Be it known that I, Robert M. Sweeney, a citizen of the United States, residing at Salisbury, in the county of Chariton and State of Missouri, have invented a new, original, and ornamental Design for an Infant's Spoon, of which the following is a specification, reference being had to the accompanying drawing, forming a part thereof.

Figure 1 is a perspective view of an infant's spoon showing my new design;

Figure 2 is a top plan view;

Figure 3 is a bottom plan view;

Figure 4 is a side elevational view;

Figure 5 is a transverse sectional view thereof taken on line 5—5 of Figure 3; and

Figure 6 is a transverse sectional view thereof taken on line 6—6 of Figure 4.

I claim:

The ornamental design for an infant's spoon, as shown.

ROBERT M. SWEENEY.
